MACHINE FOR MAKING WICKS

Samuel S. Steinberg, Boston, Mass.

Application July 1, 1943, Serial No. 493,169

4 Claims. (Cl. 153—2)

This invention relates to the manufacture of wicks of a type suitable for stove oil burners. Such wicks are made of porous, non-combustible, sheet material such as asbestos in tubular form, through which the oil is drawn up from a supply and at the upper edge of which combustion of the oil takes place. It has been found desirable to form such a wick vertically crinkled or corrugated, and in order to hold the wick in that condition, it may be reinforced with stiffening material such as wire screening.

The present invention has for an object to wrap the wick strip in the wire screening and to crimp or corrugate the product in lengths which may have their ends secured together to form the desired tubular wicks.

A strip of screening such as is suitable to be wrapped laterally about the wick strip is laterally flimsy and unstable so that it is difficult to retain it centered laterally with relation to the wick striping, which it is important to do.

The present invention, therefore, has for one object the presentation and control of the wick and the screening strip in accurate widthwise centered relation and the folding of the screening strip about the wick while this relationship between the strips is maintained. This causes the edges of the screening strip to come together on one face of the wick and to lie at substantially uniform distances from the edges of the wick.

A further object of this invention is to provide a mounting for the screen material by which widthwise portions thereof may be cut off successively and employed to wrap the wick material.

For a more complete understanding of this invention, together with further objects and advantages, reference may be had to the accompanying drawings in which.

Figure 1 is a top plan view of a wick forming machine embodying the invention.

Figure 2 is a longitudinal vertical sectional view on line 2—2 of Figure 1.

Figures 3 to 6, inclusive, are detail sectional views on the correspondingly numbered section lines of Figure 2.

Figure 7 is a fragmentary rear end elevation of the machine showing the cutting off mechanism.

Figure 8 is a perspective view of the wick strip ready to be curved into annular form and its portions secured together.

Figure 9 is a perspective view of the completed wick.

Figure 10 is a detail sectional view on line 10—10 of Figure 2.

Figure 11 is a detail sectional view on line 11—11 of Figure 10.

Figure 12 is an exploded perspective view of a

reel for supporting a roll of screening, the reel being adjustable to the width of the screening.

Referring first to Figures 1 and 2, the machine comprises a pair of spaced parallel frame members 1 and 2, the frame 1 being extended at the starting end of the machine beyond the frame 2 to form one side of a widened portion having an oppositely positioned frame member 3 parallel to the frame member 2, but much more widely spaced from the frame member 1. The frame members 1 and 3 form supports in which may be removably journaled trunnions 5 of a pair of reels 6 shown best in Figures 10, 11 and 12. Each of these reels comprises a central shaft 7, opposite ends of which form the trunnions 5, end collars 8 pinned thereto providing stops positioned outwardly of the frame members 1 and 3 and removably retaining the trunnions therein. Each of these reels has a fixed head member 9 and an axially adjustable head 10.

Spaced around the shaft 7 are a plurality, three being shown, of rods 11, each having one end headed in the fixed head 9 and extending through an opening 12 in the adjustable head 10. A collar 15 outwardly of each of the adjustable heads 10 and secured as by a set screw 16 to the shaft 7 may be employed to fix the outer limit of position of the movable head of each reel at any desired time. Each of these reels is intended to have wound thereon a length of wire screening as 20, which as shown best in Figure 11, may have one end margin hooked about one of the rods 11.

One of the reels, such as the upper reel, with a coil of screening wound thereon is positioned with its trunnions resting in the open topped bearings 22 at the top of these frames, and the screening is led down from this reel between a pair of straightening bars 24, around a roller 25, and between a pair of rotary shafts 26 and 27, each carrying a pair of disk knives 28, 29, and 33, 31. As shown best in Figure 10, these knives are arranged toward the fixed ends of the reels, the knives 28 and 33 being arranged to trim off any irregularities along the edge of the screening, and the knives 29 and 31 being arranged to progressively slit off a strip 32 of the screening along one margin thereof. All except the relatively narrow strip of screening slit off is then led down to the lower reel, the trunnions of which are mounted in the open top bearings 35 of the oppositely disposed frame members 1 and 3. A friction drive wheel 36 resting on the edge of the fixed head 9 of the lower reel and carried by a shaft 37 which carries a belt pulley 38, over which passes a drive belt 39, acts to rotate the lower reel so as to wind up the screening thereon which remains after the removal from one edge therefrom of the strip 32. This arrangement of reels permits strips 32 to be cut successively from the

edge of the screening as it passes from the upper reel to the lower reel. After the lower reel becomes completely wound with the screening and the upper reel is emptied, the positions of the reel are reversed and the adjustable heads are moved over toward the fixed heads by the width of the strip cut therefrom. Thus a wide strip of the screening is successively cut into the narrow strips, which as will later appear, are employed to wrap the wick strip and the strip 32 slit off is substantially centrally between the frames 1 and 2 no matter what the width of the screening from which the strip is cut off. The belt 39 which drives the lower reel is driven by other mechanism in the machine as will later appear.

A narrower strip of wicking such as asbestos fabric or sheet material is progressively superposed on the strip of screening 32 and the edges of the screening are turned over the edges of the wicking material and folded down thereagainst. The folding means comprises a plurality of sets of cooperating rolls. As shown three such sets of rolls are employed comprising upper rolls 50, 51 and 52 with correspondingly contoured lower rolls 53, 54 and 55, respectively. The lower rolls 53, 54 and 55 are journaled in the side frame members 1 and 2.

The upper roll 50 and the shaft 26 which carries the upper slitting knives 28 and 29 are journaled in equalizer bars 56 which are spring pressed downwardly to hold them into cooperative relation to their cooperating lower mechanisms. This may be done, for example, as shown in Figure 3 by the use of eye bolts 60 extending vertically through the equalizers 56 adjacent to their centers of length and carrying at their upper ends coil springs 61 reacting between washers 62 resting against the top face of the equalizer and nuts 63 threaded on the upper ends of the eye bolts. The eye portion of each of these bolts is secured as by a screw 65 extending therethrough and through a spacing collar 66 and into the corresponding side frame member 1 or 2.

The roller 50, as best shown in Figures 1 and 3, is provided with a pair of spaced series of points or prongs 70 positioned inwardly of tapered peripheral portions 71 which extend outwardly to end flanges 72. These prongs 70 are arranged to pass through the meshes of the screening strip 32, as shown best in Figure 3, and they project into peripheral grooves 75 in the lower roll 53. The surfaces of this roll which come opposite to the inclined portions 71 of the roll 50, as at 76, are complementally tapered so that the screening has its marginal portions bent along a pair of spaced lines outwardly of the series of prongs 70, thus to produce two starting fold lines for the opposite marginal portions of the strip 32. The prongs 70, together with the end flanges 72 of the roll 50, serve to guide the screening strip 32 in a straight line, preventing it from being deflected laterally, such screening being quite flimsy laterally so that without these provisions it would be difficult to maintain the lines of fold of its margins in parallel relation to each other.

The upper rolls 51 and 52 are mounted on equalizer bars 56, as previously described. These sets of rolls 51, 54 and 52, 55 are contoured to further bend the marginal portions of the screening around the wicking strip *a*, supplied from a roll 80 and passing around a pulley 81 and progressively led onto the upper face of the screening strip 32 between the upper rolls 50 and 51, and between the fold lines at 82 and 83 produced by the first set of rolls 50 and 53.

As shown best in Figure 4 the upper roll 51 is

10 a plain surfaced roll of a width substantially equal to the width of the space between the fold lines 82 and 83 of the screening strip and of a width to pass between end flanges 85 of the lower roll 54. This roll 51 presses the wicking strip against the top face of the screening strip 32 and the flanges 85 bend up the margins of the screening strip about their fold lines 82 and 83 into substantially vertical position, as shown in Figure 4.

15 The top roll 52, as shown best in Figure 5, has oppositely inwardly inclined peripheral surfaces 86 which engage the outer faces of the folded up margins of the screening as they leave the preceding rolls 51 and 54 and folds them down part way toward the upper face of the wicking strip *a* in the manner shown in Figure 5.

20 Next, the two strips pass between a pair of upper and lower rolls 90 and 91. The upper roll 90 is carried on a shaft 92 which may be adjusted toward the shaft 93 which carries the roll 91 by turning an adjusting screw 95 provided with a check nut 96, the lower end of this screw bearing against the top of the bearing 97 in which the shaft 92 is journaled. A spring 98 reacting between the lower face of the bearing 97 and the upper face of a slot 99 of the frame member 1 or 2 holds the shaft 92 as far above the shaft 93 as is permitted by the adjusting screws 95. The upper roll 90 is provided with end flanges 100 between which are laterally arranged gear teeth 102, and the lower roll 91 is provided with laterally arranged teeth 101 which extend between the flanges 100 and engage between the teeth 102 of the upper roll 90. These rolls thus have intermeshing gear teeth between which the folded strips are passed. These rolls also serve to complete the folding of the marginal strips of the screening flat against the upper face of the wicking strip *a*, and they also serve to laterally corrugate the strip material so that it comes out therefrom in the condition shown in Figure 8. The strip thus corrugated passes down a trough at 105 and beneath a pivoted chopping knife 106 by which it is cut off into lengths as shown in Figure 8. These lengths of material comprising the wicking strip about which the screening strip is wrapped may then have their ends secured together as by staples 110, as shown in Figure 9, to form the completed wick.

25 The chopping knife 106 is shown as fulcrumed adjacent to one end as on the screw 107 and is normally held with its cutting edge elevated as by a leaf spring 108 (see Figure 7) but it may be depressed at intervals to cut off the wrapped wicking strip as by means of a cam 109 carried by a rotary shaft 110 journaled in a bearing 111 secured to the end portion of the machine. The fulcrum bolt 107 may have a spring 112 thereon which tends to keep the knife 106 up against the end of the cutting plate 114 with which it cooperates in cutting off the folded and crimped or corrugated wicking material.

30 The various parts of the machine may be driven by power and for this purpose the shaft 110 at its inner end carries a beveled gear 120 with which meshes a bevel gear 121 on a drive shaft 122 having a belt pulley 123 at its outer end and about which a belt 124 passes from any suitable source of power (not shown). This shaft 122 may be connected through a train of gears comprising the gear 125, a change gear 126 on a link frame comprising the links 127 and

128, and a gear 129 on one end of the shaft 92. One end of the link 127 may be fulcrumed on the shaft 122 and the link 128, which is pivoted to the end of the link 127, may have a slot 130 therethrough through which the shaft 92 of the upper roll 90 passes. This arrangement provides for a power drive of the upper roll 90 which through the intermeshing teeth of this roll and the lower roll and the interposed strips positively drives the lower roll 91. The remainder of the upper rolls are shown as driven through an endless belt 135, one stretch of which passes around a belt pulley 136 on the shaft 92 and around alternately positioned idlers 137 and drive pulleys 138 on the shafts of the upper rolls 52, 51, 50, and the upper slitting knife shaft 26. The idlers 137 are positioned above the axes of the upper rolls so as to increase the extent of wrapping of the belt about the driving pulleys of these rolls. The upper stretch of the belt 135 is out of contact with the upper rolls, being passed about the idlers 139 at opposite end portions of the machine.

Similarly the lower rolls are belt driven by the belt 140, one stretch of which passes alternately about driving pulleys of the shafts of the lower rolls and idlers 141, there being one stretch of the belt held away from these driving rolls and idlers as by means of the end idlers 142.

It will be noted that this machine cuts off strips of screening material from a supply roll along one edge, and progressively wraps the margins of this screening strip about the margin of the strip of wicking, the wrapped product being then corrugated or crinkled laterally and then cut off into lengths suitable for being curved into wick formation and so secured as shown in Figure 9.

From the foregoing description of an embodiment of this invention, it should be evident to those skilled in the art that various changes and modifications might be made without departing from the spirit or scope of this invention.

I claim:

1. Mechanism for folding the margins of a strip of screening about the margins of a narrower wick strip, which comprises a series of pairs of folding rolls, one of the rolls of the first series having laterally spaced sets of spaced points projecting from its periphery for engagement within the meshes of said screening strip inwardly of the margins to be folded, and the other of said first pair of rolls having peripheral grooves to receive said points, the confronting faces of the rolls of said pair outwardly of said points and grooves being complementally inclined from parallelism with their axes to define lines of fold in said screening strip inwardly from its side edges, means for progressively laying the narrower strip between said lines of fold, the faces of the other pairs of rolls being complementally formed to progressively increase the bend at said lines and finally to fold said screening margins back toward the central widthwise portion of said strips and against the exposed face of said narrow strip, a pair of intermeshing laterally toothed rolls between which said wrapped strip passes to corrugate said wrapped strip transversely, and means for driving said pairs of rolls.

2. Mechanism for folding the margins of a strip of screening about the margins of a narrower wick strip, which comprises a series of pairs of folding rolls, one of the rolls of the first series having laterally spaced sets of spaced points projecting from its periphery for engagement within

the meshes of said screening strip inwardly of the margins to be folded, and the other of said first pair of rolls having peripheral grooves to receive said points, the confronting faces of the rolls of said pair outwardly of said points and grooves being complementally inclined from parallelism with their axes to define lines of fold in said screening strip inwardly from its side edges, means for progressively laying the narrower strip between said lines of fold, the faces of the other pairs of rolls being complementally formed to progressively increase the bend at said lines and finally to fold said screening margins back toward the central widthwise portion of said strips and against the exposed face of said narrow strip, a pair of intermeshing laterally toothed rolls between which said wrapped strip passes to corrugate said wrapped strip transversely, means for cutting said corrugated wrapped strip into lengths, and means for driving said pairs of rolls.

3. A machine of the class described, comprising a pair of spaced frame members, a series of pairs of rolls of which one roll of each pair is between and is journaled in said frame members, means for yieldingly pressing the other roll of each pair toward said one roll, means for presenting a relatively wide strip of material between the first pair of rolls, the rolls of said first pair being formed complementally to bend the marginal portions of said strip inwardly, means for presenting a narrower strip in superposed relation to said wide strip between said marginal portions, later pairs of rolls being complementally formed to progressively fold said marginal portions inwardly and wrap said narrower strip within said wide strip, a pair of said rolls positioned after said folding and wrapping rolls having intermeshing teeth between which said wrapped strip passes and acting to laterally corrugate the wrapped strips, means for rotating one of said toothed rolls and thereby rotating the other of said toothed rolls to feed as well as corrugate said wrapped strips, and a belt drive between each of said corrugated rolls and one each of said pairs of rolls.

4. A machine of the class described, comprising a pair of spaced frame members, a series of pairs of rolls of which one roll of each pair is between and is journaled in said frame members, means for yieldingly pressing the other roll of each pair toward said one roll, means for presenting a relatively wide strip of material between the first pair of rolls, the rolls of said first pair being formed complementally to bend the marginal portions of said strip inwardly, means for presenting a narrower strip in superposed relation to said wide strip between said marginal portions, later pairs of rolls being complementally formed to progressively fold said marginal portions inwardly and wrap said narrower strip within said wide strip, a pair of said rolls positioned after said folding and wrapping rolls having intermeshing teeth between which said wrapped strip passes and acting to laterally corrugate the wrapped strips, means for rotating one of said toothed rolls and thereby rotating the other of said toothed rolls to feed as well as corrugate said wrapped strips, and a belt drive between each of said corrugated rolls and one each of said pairs of rolls, said drive including idlers positioned between adjacent rolls of the several pairs and about which and said adjacent rolls one stretch of each belt passes, the other stretch of each belt being out of contact with said rolls.

SAMUEL S. STEINBERG.
